UNITED STATES PATENT OFFICE

SAMUEL ALIMENA AND WILLIAM NAUMANN, OF SCRANTON, PENNSYLVANIA

SLIDING HAIR AND WAVE CLIP

Application filed November 11, 1932. Serial No. 642,298.

This invention relates to a clip used in waving hair and the like, the general object of the invention being to provide a U-shaped member of flexible material and a sheath in which one limb of the member is slidably arranged, so that the clip can be easily and quickly engaged with a bunch of hair, and just as easily released from the hair without disarranging the hair.

10 This invention also consists in certain other features of construction and in the combination and arrangement of the several parts to be hereinafter fully described, illustrated in the accompanying drawing, and 15 specifically pointed out in the appended claims.

In describing the invention in detail reference will be had to the accompanying drawing wherein like characters denote like 20 or corresponding parts throughout the several views, and in which:

Figure 1 is an edge view of the device with a part broken away.

Fig. 2 is a top plan view thereof.

25 Fig. 3 is a top plan view with the clip partly pulled from the sheath.

Fig. 4 is a section on line 4—4 of Fig. 3.

As shown in this drawing, the device comprises a substantially U-shaped member 30 1 formed of spring metal or the like and an arcuate sheath 2 in which one limb of the member 1 is slidably arranged. One end of the sheath is closed and its other end is opened to receive said limb of the member 35 1 and the open end is reduced as shown at 3 to prevent the large end 4 of said limb from being entirely removed from the sheath as shown in Fig. 3.

The pin or member 1 is pulled out of the 40 sheath as far as possible, and then the sheath is placed under that part of the hair to be waved or engaged by the device. The sheath is held in position with the finger of one hand, by slightly holding it against 45 the head. Then the free limb of the pin or member 1 is lifted by the thumb nail or another part of the hand and slipped over the bunch of hair with the middle finger so that when the free limb is released, the 50 device will clamp the hair between said free

limb and the sheath. In removing the device, the free limb is moved upwardly, and then the entire device lifts from under the hair so that it will not disarrange the hair, as it is being removed.

55 Thus we have provided a simple device which can be easily and quickly put in place and removed, and when being removed will not disarrange the hair.

It is thought from the foregoing description that the advantages and novel features of the invention will be readily apparent.

It is to be understood that changes may be made in the construction and in the combination and arrangement of the several 65 parts provided that such changes fall within the scope of the appended claims.

Having thus described our invention what we claim as new is:

1. A device of the class described comprising a substantially U-shaped member formed of spring material and a sheath in which one limb of the member is slidably arranged said sheath having one end closed and its other end open with said one limb 70 passing through the open end and said sheath being of a length substantially equal to the length of said one limb.

2. A device of the class described comprising a substantially U-shaped member 80 formed of spring material, a sheath having one end closed and its other end open, and in which one limb of the U-shaped member is slidably arranged, the open end being reduced and the extremity of said limb being 85 enlarged to prevent said limb from being entirely removed from the sheath.

In testimony whereof we affix our signatures.

SAMUEL ALIMENA. 90
WILLIAM NAUMANN.
